C. P. Goepel.

ATTORNEY

UNITED STATES PATENT OFFICE.

JULIEN STRANDERS, OF BROOKLYN, NEW YORK, ASSIGNOR TO HARRY B. KRUGER, OF NEW YORK, N. Y.

DISPLAY DEVICE.

1,334,056.

Specification of Letters Patent. Patented Mar. 16, 1920.

Application filed June 23, 1919. Serial No. 306,083.

To all whom it may concern:

Be it known that I, JULIEN STRANDERS, a subject of the King of England, and a resident of Brooklyn, county of Kings, in the 5 city and State of New York, have invented certain new and useful Improvements in Display Devices, of which the following is a specification.

This invention relates to display devices 10 and broadly considered contemplates the provision of a very simple and inexpensive device of this character which will afford a novel and attractive advertisement for various commodities.

15 In particular, my present invention consists in the provision of a carton of exaggerated size having suitable advertising matter printed on its several surfaces, and one wall of the carton body being provided with 20 an integral panel extending along its longitudinal edge and having a marginal contour corresponding to that of a fictitious article, presumably adapted to be contained within the carton and thereby simulating an arrangement of such a fictitious article in juxtaposition to the carton.

It is another important object of my invention to provide a display device for the purpose stated, which is formed from a single blank of cardboard or other flexible material and is provided with a collapsible body 30 with the display panel extending from one wall thereof, another of the body walls having an extension rigid therewith and in effect constituting a continuation thereof which is cut out from an adjacent body wall and is adapted to support the carton and the display panel in an obliquely inclined 35 position.

40 Having the aforementioned objects in view, the present invention comprehends certain novel and improved combinations of mechanical elements, and the structural characteristics thereof, as will be more fully developed in the following description and subsequently incorporated in the subjoined claims.

50 In the accompanying drawing wherein I have illustrated one practical embodiment of my invention and wherein like reference characters designate corresponding parts throughout the several views,

55 Figure 1 is a perspective view illustrating the device arranged in display position;

Fig. 2 is a transverse sectional view;

Fig. 3 is a fragmentary perspective view; and

Fig. 4 is a plan view showing the device 60 folded or collapsed.

Preferably, the device as illustrated in the accompanying drawing is formed from heavy cardboard, though if desired aluminum, tin or other sheet metal having the requisite stiffness may be employed. The 65 device includes a carton of exaggerated size, generally indicated by the numeral 5. This carton is formed by scoring the sheet of flexible material along longitudinal parallel lines at spaced intervals to thereby provide 70 the hingedly connected body walls 6, 7, 8 and 9 respectively. The walls 6 and 7 of the carton have suitable advertising matter printed or otherwise delineated upon their outer surfaces as shown in Fig. 1 of the 75 drawings. The walls 7 and 9 are transversely scored adjacent to their opposite ends to provide the inwardly foldable flaps 10. The wall 6 is similarly provided at its ends with a relatively long flap 11 which is 80 scored adjacent to its free end as at 12 to provide a sealing tab 13. Thus, from reference to Fig. 2 of the drawing, it will be observed that the ends of the carton may be 85 securely closed by first folding the flaps inwardly toward each other and then folding the flaps 11 inwardly and downwardly upon the flaps 10 and inserting the tab 13 between one end of the flaps 10 and the wall 8.

The wall 6 of the carton is provided with 90 an extension panel 14 which projects laterally from one longitudinal edge of said wall and is properly cut so that the outline thereof corresponds to that of a fictitious article which is presumably adapted to be 95 contained within the carton. The surface of this panel is also properly marked or ornamented in correspondence to the marking upon the article which is actually offered for sale and of which the fictitious 100 article is an enlarged reproduction. This panel 14 which is an integral continuation of the wall 6 of the carton is cut from one end of the flexible sheet of material. The wall 9 which is formed from the other end 105 of the sheet is scored adjacent to its end to provide a bendable flap or strip 15 which is adapted to be extended at right angles to the wall 9 and adhesively or otherwise permanently secured to the rear face of the panel 110

14 contiguous to its juncture with the longitudinal edge of the carton wall 6. The wall 9 is also provided with a rigid integral extension 16 disposed in the plane of said wall, which extension is cut out from the wall 8 of the carton body, thereby providing in the latter wall an opening 17 which is designed to receive the extension 16 when the device is folded or collapsed. A reinforcing strip 18 is secured upon the inner face of the wall 9 and upon the corresponding face of the extension 16. This strip effectively prevents the bending or deflection of the extension 16 relative to the wall 9. The extension 16 is adapted to rest at its end upon the supporting surface at a point in spaced relation to the juncture of the body wall 7 and 8 of the carton which also contacts with the support. Thus it will be seen that the extension 16 serves to support the carton and the display panel 14 in an obliquely inclined position relative to the support upon which the device may be placed, and therefore exposing to view the advertising matter contained upon the surfaces of the walls 6 and 7.

When the device is set up in its display position in a window or upon a show case or counter, to the casual observer it will appear as though the article had been removed from the carton and arranged in superposed relation therewith, and when considered in conjunction with the advertising matter appearing upon the surfaces of the carton and the panel, affords an original and attractive advertising display, without necessitating the use of the article itself, which is manufactured for sale to the retail trade. As is well known, the exposure of many commodities in store windows or show cases to the effects of the sun and light results in a deterioration in the quality of the commodity which frequently entails an appreciable financial loss. While I have, for the purposes of illustration of the present improvements, shown the display panel in the familiar form of metal tube, such as that in which shaving cream, tooth powder and similar toilet preparations are usually vended, it is of course manifest that this panel may be fashioned in numerous other shapes for the purpose of advertising, in conjunction with a carton or container, for various other commercial articles. Also, as I have indicated in the drawing, the closure flaps 11 for the ends of the carton may likewise have suitable advertising matter printed thereon.

From the foregoing description considered in connection with the accompanying drawing, the construction, manner of use and several advantages of my invention will be clearly and fully understood. The device may of course be produced in various sizes, but in every case, for the purpose

of enabling the casual observer to obtain a complete realization of the character of the commodity advertised, the size of the carton and the display panel will be greatly exaggerated in comparison with the actual size 70 of the article and the carton in which the same is vended. When the display device is not in use, the several walls of the carton may be compactly folded as seen in Fig. 4 by simply pulling the tabs 13 and the flaps 75 11 outwardly and then collapsing the carton body. In such collapse of the carton, the supporting extension 16 will fit neatly within the opening 17 of the carton wall 8 as clearly shown in Fig. 4. Thus, it will be 80 appreciated that a large number of the collapsed display devices may be compactly arranged within a relatively small storage space. As the device in its entirety is formed from a single sheet of material and may be 85 cut out and arranged in condition for use by means of a few minor operations it will be appreciated that the invention can be manufactured and sold or furnished gratis by the manufacturer to retailers, at a very small 90 cost.

In the preceding description and the accompanying drawing I have disclosed one practical embodiment of the invention, which, however, may likewise be exemplified 95 in numerous alternative constructions. Accordingly the invention as herein claimed is to be considered as inclusive of all legitimate equivalents for the various elements employed as well as other contemplated arrangements thereof, which may satisfactorily accomplish the desired results.

I claim:

1. A display device comprising a complete carton for a single article of merchandise having a panel extending along the longitudinal edge of one of its walls and disposed in the same plane therewith, said panel being formed and superficially marked to represent a fictitious article presumably 105 adapted to be contained within the carton, and thereby simulating the said article arranged in juxtaposition to the carton.

2. A display device comprising a collapsible carton complete in itself and having 110 hingedly connected body walls, an additional panel integral and rigid with one of said walls and disposed in the plane thereof, the conformation of said panel corresponding to that of a fictitious article presumably adapted to be contained within the 115 carton and thereby simulating the article arranged in juxtaposition to the carton.

3. A display device comprising a collapsible carton having hingedly connected body walls, a panel integral and rigid with one of said walls and projecting from one longitudinal edge thereof, the conformation of 125 said panel corresponding to that of a fictitious article presumably adapted to be con- 130

tained within the carton and thereby simulating the article arranged in superposed relation to the carton.

4. A display device comprising a carton 5 complete in itself for the reception of a single article and a relatively immovable panel simulating a fictitious article presumably adapted to be contained within said carton and projecting from one longitudinal 10 edge of the carton at the juncture of adjacent walls thereof, and in fixed juxtaposed relation to the carton.

5. A display device comprising relatively movable body walls hingedly connected to 15 each other along one of their longitudinal edges, and adapted to be angularly arranged relative to each other when the device is disposed in display position to form a rectangular closed carton, and a rigid display 20 panel integral with one of said walls and projecting in the plane thereof from the hingedly connected edges of said walls.

6. A display device comprising a collapsible carton consisting of a single sheet of material scored at spaced points to provide a 25 plurality of hingedly connected walls, one end of the sheet of material being cut to provide a panel integral and rigid with one of said walls and having a marginal contour 30 conforming to the contour of a fictitious article presumably adapted to be contained within the carton.

7. A display device comprising a parallelogrammatic body structure constituting a 35 completely closed carton of exaggerated size, and a display panel adapted to be arranged in juxtaposed relation to said structure and simulating in outline and superficial marking a fictitious reproduction of the market-

able article presumably adapted to be contained within said carton. 40

8. A display device comprising a parallelogrammatic collapsible body structure constituting, when in display position, a completely closed carton of exaggerated size, 45 and a display panel rigid with one wall of said structure and simulating in outline and superficial marking a fictitious reproduction of the marketable article presumably adapted to be contained within said carton. 50

9. A display device comprising a parallelogrammatic collapsible body structure constituting, when in display position, a completely closed carton of exaggerated size, 55 a display panel rigid with one wall of said structure and simulating in outline and superficial marking a fictitious reproduction of the marketable article presumably adapted to be contained within said carton, and another wall of said structure having means 60 extending in a plane at right angles to said panel to support the device in display position.

10. A display device comprising a collapsible body structure formed from a single sheet of material and having relatively movable walls adapted to be arranged to constitute a completely closed carton of exaggerated size, and a fictitious reproduction 65 of the marketable article carried by one of 70 said body walls in projected relation thereto and presumably adapted to be contained within said carton. 75

In testimony that I claim the foregoing as my invention, I have signed my name hereunder.

JULIEN STRANDERS.
